UNITED STATES PATENT OFFICE.

DAVID F. HARTFORD, OF BOSTON, MASSACHUSETTS, ASSIGNOR OF ONE-HALF TO THOMAS T. HARTFORD, OF SAME PLACE.

SOLE-ROUNDING MACHINE.

SPECIFICATION forming part of Letters Patent No. 274,939, dated April 3, 1883.

Application filed November 3, 1882. (No model.)

To all whom it may concern:

Be it known that I, DAVID F. HARTFORD, of Boston, in the county of Suffolk and State of Massachusetts, have invented a new and useful Sole-Rounding Machine, of which the following is a specification.

My invention relates to improvements in machines for rounding up sole-blanks, in which the blank is cut to the proper contour by a traveling knife, and in which the knife is guided by a fixed pattern.

My objects are as follows: to avoid waste of material and labor by making the guide-pattern of metal thin enough to be easily cut to the required shape by a die or the like; to guide the knife without bringing it in contact with the edge of the pattern; to so mount the knife that it will swivel or turn, as required by the variations of direction of the contour of the pattern, so as to always present its cutting-edge properly to the blank; to make the knife adjustable for cutting bevel-edges, or larger or smaller than the pattern; to so arrange the supports of the clamps for holding the blank that the clamps may be readily changed to accommodate different sizes of soles, and to provide facilities for adapting the knife-carrying mechanism to the varying sizes of the clamps.

In the accompanying drawings, which illustrate a sole-rounding machine with all my improvements as embodied in the best way now known to me, Figure 1 is a plan or top view of the complete machine, a covering-plate being removed to show the chain and its connections.

Fig. 2 is a side view, on a smaller scale, of the machine shown in Fig. 1. When a sole-blank is in position indicated by the dotted lines the upper clamp is lowered. Fig. 3 is a side view of the knife-carrying slide detached from its carriage. Figs. 4 and 5 are respectively end and side views of the yoke which carries the knife, and which is secured to the inner end of the slide, the dotted lines in Fig. 5 indicating the different positions of the yoke and knife. Fig. 6 shows the knife, its connection to the arms of the yoke, and the double crank and the grooved wheel for keeping the cutting-edge of the knife in proper position. Fig.

7 shows the knife detached, and two views 50 of the rod that connects it with the double crank and controlling-wheel. Fig. 8 shows the manner of attaching the upper clamp to the lever.

A A' are clamps for holding the sole-blank, 55 which is laid on the clamp A', as indicated by dotted lines in Fig. 2, while it is being rounded up to the proper contour. The clamp A is detachably secured to the follower a, which is connected to and raised or lowered by the lever a', pivoted to the arched bar b, which is rigidly secured to the base B.

Instead of the heavy cast-iron guide-pattern heretofore used, which required much labor to finish it to the proper size, was placed in 65 contact with the sole-blank, and by contact with the edge of which the knife was guided, I employ a pattern, D, having a contour corresponding to that desired for the finished sole, and made of metal thin enough to be readily 70 cut or stamped to the proper shape. This is supported on posts a² a³. The tops of these posts are turned down to proper-sized dowels, which dowels pass through holes in the thin metal pattern and enter holes in the clamp A', 75 and serve to hold it in its position on the pattern D, as shown in Fig. 2.

The advantages arising from separating the guide-pattern and sole-blank by placing a clamp between them are that the cutting-edge 80 of the knife cannot be dulled by contact with the metal pattern, that the friction may be greatly reduced, and a very thin pattern be used.

The knife K is mounted on a slide, G, provided with a grooved wheel, g, the groove in which is kept in contact with the pattern D by means of the coiled spring H, which acts on a pinion meshing in a rack fast to the slide G. A long coiled spring is preferable, because 90 its tension or power is but little affected by the slight back-and-forth motion of the slide. This slide G is mounted on wheels to lessen friction, which wheels rest on the carriage F. The carriage F is fast to a link of a chain, f, 95 passing around pulleys f' f'', turning on journals secured in brackets in the posts a² a³. (See Figs. 1 and 2.) This chain is caused to

travel by suitable gearing, and the knife-carriage F, being rigidly attached to one of its links, must therefore travel with it and always maintain the same position in relation to the link to which it is attached.

It will be readily understood that the slide G has no motion independent of the carriage except that given by the contour of the guide-pattern, and that consequently it and the knife 10 travel with the carriage.

It is evident from the shape of a sole that the position of the cutting-edge of the knife must vary as it travels around its edge, and for this reason, in order to keep the cutting-edge of the knife always properly presented to the sole-blank, the knife K is journaled at each end, so as to turn freely, and in order to provide a leverage on which the blank may act to turn the knife as its direction is changed 15 by the contour of the blank the cutting-edge of the knife is set slightly to one side of a line passing through the axes of the knife. This arrangement answers the purpose so long as the knife remains in the leather; but if there 20 should be a slight break in the continuity of the leather the knife in passing that break might be deflected and not present its edge properly on striking the other side of the break. To avoid this difficulty I control the knife-edge by means of the grooved wheel g, turning 25 on the wrist of a double crank, g' g², the axis or shank of this crank being in line with the axes of the knife-journals. To this crank the knife is connected by means of the rod g³. (See Figs. 3, 4, and 7.) The slide G is always 30 at right angles to the link of the chain, to which its carriage is fastened. The wheel g follows the contour of the pattern, and in turning a bend or angle the bearing of this wheel 35 on the pattern will come out of line with the axes of the crank and the wheel. This will cause a side strain on the wheel, which will immediately throw the crank until the bearing of the wheel and their axes come again 40 in line, and the knife, being connected as above described, will be correspondingly turned, and thereby properly present its cutting-edge.

It is often required to cut the edges of the sole to a bevel, and the taps are usually made 45 of a different size from the sole for these reasons. The journal-boxes k² k³ of the knife K are supported on the ends of the arms of a yoke, k. This yoke k is clamped to a slotted lug on the slide G by means of the screw k' and plate k⁴. (See Figs. 3 and 5.) Both the journal-boxes and a slot in the yoke k are curved from the same center, which is a point in the middle of the knife, and in line with the axes of the knife. The plate k⁴ has a projection that enters the curved slot in the yoke k.

It is evident that on loosening the clamp-screw k' the yoke and knife can be partially rotated, thereby inclining the knife to the required bevel without changing the position of

its middle. By loosening the clamp-screw k' and turning the set-screw k⁶ the edge of the knife can be changed in its relation to the periphery of the wheel g, so as to cut the blank larger or smaller than the pattern. The yoke 70 is held against the end of the set-screw k⁶, when the screw k' is loosened, by the spring k⁵. (Seen in Figs. 1 and 3.)

Two sets of clamps A A'—one for adults' and the other for children's sizes—and a number of patterns corresponding to the varying sizes of these two classes, are requisite, and in order to readily change a pattern when clamps for one class are used a hook, a⁴, is pivoted to the clamp, so that when the clamps are brought together and nothing is between them the hook a⁴ enters an opening, a⁵, in the clamp A', and catches and retains it, so that it will be lifted off from the pattern when the lever a' is depressed, and leave the pattern free to be removed and another to be substituted.

To change the clamps from one class to another the clamp A is released by loosening the screw a⁶, the clamp A' is lifted off, and the post a² is moved toward the post a³ by loosening the clamp-screw a⁴, and secured in proper position by tightening that screw. The chain f has its links so proportioned that one or more of them may be removed, and thereby make the length of the chain conform exactly to the change in 85 the distance between the posts.

It is obvious that while two sizes of clamps might be used for all sizes of shoes it would be advisable to have two or more sizes for each class, especially when their soles are to be rounded up, and which, for a large shoe, would project to an objectionable extent beyond the edges of the clamps, the chain being adapted to the different sizes by adding or removing a link, as hereinbefore described.

I claim as my invention—

1. In a sole-rounding machine, the guide-pattern, in combination with clamps for holding a sole-blank, said pattern being separated from and resting below the blank-bearing face 100 of the clamp, substantially as and for the purposes set forth.

2. In a sole-rounding machine, a knife journaled at each end and adapted to be partially rotated, having its cutting-edge to one side of 115 a line passing through the axes of its journals, substantially as and for the purposes set forth.

3. The combination, with the knife above described, of a double crank having its shaft in line with the axes of the knife, and a wheel mounted on the wrist-pin of this crank and held in contact with the edge of the guide-pattern, substantially as and for the purposes set forth.

4. The combination, with the knife above 125 described, of a forked yoke supporting the journal-boxes of the knife, and adapted to be partially rotated in a circle, as described, and to be advanced or retracted, substantially as and for the purposes set forth.

5. In a sole-rounding machine, the combination, with a clamp attached to a lever, as described, and a clamp resting on posts, of a hook pivoted to the post-clamp and adapted to catch and retain the other clamp, substantially as and for the purposes set forth.

6. In a sole-rounding machine, clamp-supporting posts adapted to be set at different dis-

tances from each other, in combination with a chain propelling the knife-carriage and adapted to be lengthened or shortened, substantially as and for the purposes set forth.

DAVID F. HARTFORD.
